UNITED STATES PATENT OFFICE.

WILLIAM A. DOBSON, OF BRIDGEPORT, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed November 26, 1924. Serial No. 752,316.

This invention relates to casings in which a typewriting machine may be encased and operated with a minimum of noise. In casings of this character, provision is made for 5 extending the keyboard-section of the machine through an opening in the front, in order that the keys may be operated; and provision is also made for the extension through the casing and for the travel there- 10 along of the operating arms which are mounted on the carriage and move therewith on the machine.

One feature of this invention relates to the construction of the casing with the object in view of minimizing the cost of manufacture.

This invention relates further to the construction of the casing which is made of a plurality of sections, including two side 20 frames or plates, which may be made of cast metal, such as iron, brass, or die-cast metal, a sheet-metal plate forming the front section and having an opening for the protrusion of the keyboard, and a rear section 25 also made of sheet-metal and having at its uppermost end a hinge upon which the cover is swung. Both the front and rear sections are fastened to the end frames, and the resulting four sections are in turn fastened to 30 a base-plate, which may also be made of sheet-metal.

One feature of this invention relates to the manner in which the inside panels, provided for further deadening the noise, are 35 secured to the outer panels, forming a double wall. Said inside panels have formed at their ends channels in which felt abutment strips are seated.

Another feature relates to means for 40 clamping the machine within the casing and against the front plate thereof, thus preventing the leakage of sound-waves from the borders of the opening in the front wall through which the keyboard extends. Said 45 means comprise a rock-shaft operatively mounted on the base-plate of the casing and have at the inner end a shoe fastened thereon and bearing against the frame of the machine. The rock-shaft is provided at the 50 other end with means for operating and locking the same in its effective position.

Another feature is the provision of felt strips instead of the usual tubular sealing 55 cushions, in the opening formed between the casing and the cover through which the

carriage-controlling levers extend to the exterior of the casing. Means are provided whereby the opening formed between the casing and the cover through which the levers controlling the carriage extend may 60 be adjusted. Said means comprise an adjustable plate co-operating with the lock which holds the cover closed.

There are also provided novel means for holding the front pad underneath the key-levers, said means comprising an upwardly-extending plate which forms an integral part of the base-plate and has formed at its ends inwardly-extending bends for effectively supporting the felt pads therein.

Other features and advantages will hereinafter appear.

In the accompanying drawings,

Figure 1 is a front view, in elevation, showing a sound-deadening casing partly 75 in section.

Figure 2 is a cross-sectional view of a lock for forcing a typewriting machine against the front wall of the casing.

Figure 3 is a horizontal cross-sectional 80 view of the casing, showing the lock in its normal or effective position.

Figure 4 is a vertical cross-section of the casing, showing a typewriting machine enclosed therein.

Figure 5 is a perspective view, showing the outer component parts or sections of the casing.

Figure 6 is a perspective view, showing one end inner panel and a portion of a rear 90 inner panel relatively positioned.

Figure 7 is a rear cross-sectional view, in elevation, showing the construction of the end frames and the manner in which the cover is fitted to the casing.

Figure 8 is a fragmentary cross-sectional view, in elevation, showing the lock which holds the cover closed and adjustments therefor.

Figure 9 is a plan view of the lock illustrated in Figure 8.

The Underwood typewriting machine comprises a main frame 10 provided with a forward extension 12 in which are positioned banks of keys for operating type-bars (not shown), to cause types carried thereby to print against a platen 13 journaled in the end walls of a platen-frame. The platen-frame forms part of a carriage 15 mounted for letter-feeding movement 110

upon rails (not shown). The carriage is provided with various forwardly-extending finger-pieces 16 for operating the same, and the platen.

5 For deadening the sounds arising in the typing operation, there is provided a sound-deadening casing or hood comprising a body-part and a cover 19. The body-part is made up of a plurality of parts assembled together 10 by means of fastening members 20, and comprises two end frames 21 which may be either ordinary sand-castings or die-castings, one rear plate 22 and one front plate 23 which may be made of sheet-metal, and the 15 four are assembled together and mounted upon a base-plate 24. The front section is provided with an opening 25 for the keyboard, and is also provided at its uppermost edge with a forwardly and upwardly extending angular bend 26 for the purpose of 20 stiffening said plates and for supporting a felt strip sealing the opening provided for the carriage-controlling finger-pieces 16. The rear section is provided at its uppermost 25 edge with a hinge 28 fast to the cover 19, and also fastened to the back plate 22 by means of screws 29.

The end frames 21 may be distinguished from each other as the right and left frames.

30 The former is a plain casting having a rib 30 for reinforcing the bottom and side edges and is provided with holes 31 matching the holes 32 in the base-plate and the holes 33 and 34 respectively matching similarly-numbered holes in the front and rear plates. It will be noted that holes 18 are provided in the left frame 21 for matching similarly-numbered holes in the base-plate 24 and in the front and rear plates 23 and 22 respectively. The top of the base-plate is covered with a sheet 59 of sound-deadening material, which may be felt, and at the forward end of the plate overlies the lower end or foot 61 of a front felt lining 60, thus 45 holding the latter in its proper position. Beneath the plate 24 there is provided a felt pad 14 as a protection for the table upon which the casing stands.

The left frame carries upon it a spring 50 39 for raising the cover 19 and a lock for holding the cover closed against the pressure of the spring tending to open the same. The advantage of mounting these two devices in the same frame is obvious, as such 55 a construction lends itself to the building of the casing of light material, and eliminates the distortion that might be set up by the spring if the lock had been placed in one frame and the spring in another, as has 60 been the custom heretofore in similar sheet-metal casings. In Figure 4 the means for raising the cover are illustrated and comprise an arm 35 pivoted on a pin 36 fast upon the left end frame 21 in the holes 40 and 65 mounted between the ear 17 and the end

frame 21. Said arm 35 is operatively connected by means of a slot 37 to a roller 38 fast to the cover 19. A spring 39 wound around the pin 36 has one of its ends fast on the arm 35 while the other end is fast to the frame. Improved means for raising the cover including means for regulating the tension of the spring and means for gradually checking the travel of the cover are disclosed in the application of Joseph Lindburg, Serial No. 726,424, filed July 17, 1924 (now Patent No. 1,603,781, dated October 19, 1926).

Mounted in the same left side frame there is provided the lock which normally holds the cover closed against the pressure of the spring 39. Said lock is released by means of a button 41, shown in Figures 8 and 9, which is operatively connected to a pawl 42 rocking on a pin 43 and fast to the cover 19. Said pawl is controlled at its lower end by a plate 44 also fast to the cover 19 by means of screws 45. A spring 46 actuates the pawl 42 forwardly to engage a locking piece 47 adjustably mounted on the casing by means of adjusting screws 48 and a binding screw 49. By means of this adjustment there may be regulated the pressure of the opposite felt strips 27, 81 that close the slot through which protrude the carriage-controlling finger-pieces. A tongue 50 formed at right angles to the cover-latch 42 at its lowermost end, is engaged by the inner end of a sliding stem 51, which is limited in its movement by a stop-screw 52 and carries at its outer end the button 41, which is returnable to a normal position by means of a spring 53.

The base-plate 24 has formed at its forward end the front closure 54 under the key-levers, and is provided with clearance slots 55 for the different keys, and at the ends the front closure extension is provided with bent-in clips 56 for supporting a felt strip 57 also provided with slots 58 for clearing the keys of the machine. In order that the felt strip 57 may be effectively held in place, there is provided a metal strip 75 which is supported at the ends by the bends 56 of the front closure 54. The metal strip 75 is slightly bent inwardly at the center so that it will hold the lower edge of the felt strip 57 against the front closure 54. There are also provided bent-up portions 11, which form an integral part of the base-plate 24, each portion having holes 113 corresponding with similarly-numbered holes in the front plate 23 for fastening the two members together.

For the purpose of further deadening the sounds arising from the operation of the machine, the end frames and the rear plate of the casing are provided with plates or panels 62 and 68, shown in a perspective view in Figure 6. Felt strips at the uppermost

edges of the panels co-operate with similar felt abutments in the cover for further preventing the leakage of sound-waves through the opening between the two panel-members.

5 The inner side panels 62 are shaped for forming a sound-deadening air space between themselves and the outer end frames, and have at their lowermost edges reflex folds forming reinforcing ribs 63 which terminate with rearwardly-extending tabs 64 designed to enter corresponding openings 65 in the base-plate 24. Said panels 62 are held in place by the lower ribs 30 of the frames 21. At the uppermost edges the 10 side panels 62 are also bent forming a channel 66 for receiving a felt strip 67. The rear panel 68 is placed parallel to the rear plate 22 forming an inner wall therefor, and is similarly reinforced at its lowermost edge 15 by means of a rib 69, and terminates with inwardly-extending bends forming tabs or tongues 70 for fitting corresponding openings 71 to the rear of the base-plate 24, and is provided at its uppermost edge with a 20 channel 72 which receives the strip 73. The ends of the rear panel 68 are bent inwardly forming the rib 74 which reinforces the same and fits the outline of the side panels 62.

The inner wall of the front plate 23 needs 25 now to be described. It consists generally of a lining of some sound-deadening material such as felt. The lining 60 is positioned or retained by means of a channel-piece 76 which is fastened to the plate 23 by rivets 77. Said piece 76 is shown in Figure 4, and extends the full length of the front plate. Its section is bent rearwardly and upwardly, to form a retainer for the felt sealing strip 27, and is then folded upon 30 itself and runs downwardly forming a resilient extension 78 bearing on the lining 60. The holes 79 are provided so that the rivets 77 may be supported while the piece 76 is assembled. The channel formed between 35 the piece 76 and the front plate at its uppermost edge receives the felt strip 27 which co-operates with another felt strip 81 supported by a metal strip 82 fast on the cover 19 by means of fasteners 83.

50 The cover 19 is mounted to swing on the hinge 28 and is provided at the rear with a continuous felt strip supported by a channel 84 formed by the extension of a spaced inner sheet-metal lining 85 which is fastened 55 to the cover 19 by means of fasteners 86 and 87. The fastener 86 is assembled through a hole 88 in the lining 85, which forms an extension 89 for supporting a glass 90 through which the typing in the machine is rendered 60 visible. The glass 90 is otherwise supported by a plate 91 and screws 92. The sides of the cover 19 are also provided with felt strips 93, shown in Figures 1 and 7. A metal strip 94 fast to the sides of the cover 65 forms a double channel supporting both side

linings 95 and the strips 93. The strip 94 is fastened to the cover 19 by means of fasteners 96 and extends inwardly, then downwardly and is bent upwardly again to form a resilient extension 97 which holds the ends 70 of the side linings 95. Holes 80 are provided to facilitate the assembling of the fasteners 96.

A typewriter may be inserted in this casing, when the cover is raised, with its keyboard-extension 12 projecting forwardly through a hole in the front plate of the casing into a position where it may be conveniently operated and for the purpose of securing the machine within the casing, and 75 for forcing the same against the front plate thereof to thus prevent the leakage of sound-waves from the borders of the opening through which the keyboard of the machine extends, there are provided clamping means 80 which may comprise a rock-shaft 98 journaled in bearings 99 fast to the base-plate 24. Said rock-shaft 98 is provided at its inner end with a shoe 100 covered with some soft material 101 and bearing against the 85 frame 10, thus forcing the machine forward against the front plate 23. The other end of the rock-shaft 98 carries an operating arm 102 mounted on a pivot 103 fast on said shaft 98. The arm 102 is made of some 90 resilient material and may be engaged with a hook 104 fastened to the base-plate, and held against the machine under tension due to the resiliency of said arm 102, as shown 95 in Figures 4 and 5, or it may be thrown 100 backwardly to its ineffective position, as shown in Figure 2, for removing the machine. It should be noted that the normal position of the arm 102 is shown in dot-and-dash lines in Figure 4, and that in order to 105 lock the arm 102 the same has to be sprung downwardly and swung under the hook 104, a downwardly-extending portion 105 engaging with a detent-hole 106.

In order that the carriage-controlling finger-pieces, which extend out of the casing through the opening formed between itself and the cover, may slide along the slot which is parallel to the bottom of the casing upon which the machine rests, the carriage and the finger-pieces therefore must be 110 slid able in a line with said opening. It is also desirable to insert the machine into the casing without altering the same in any way, but due to the fact that the Underwood 115 typewriting machine is generally provided with feet of different heights in order to slightly incline the carriage guides and thus assist the carriage in its letter-feeding travel, the right-hand feet 108 are built up by means of an interposing washer 109, while the left-hand feet 110 which have no washer interposed are left lower. This arrangement, however, is not essential for the operativeness of the machine and may therefore 120 125 130

be dispensed with, and is in fact eliminated when the machine is enclosed in the casing by building up the lower feet 110 an amount corresponding to the thickness of the washer 109 by means of a plate 111.

The feet of the typewriter are made of two parts, a metal core 112 and a rubber covering moulded around said core which is made of square section material, is turned 10 down in the center 114 and is threaded at the end 115 for fastening the same to the frame of the machine. The advantage of this construction will be apparent as it prevents the rubber from rotating around the 15 core 112 while the feet are seized to screw the same in and out of the frame.

Variations may be resorted to within the scope of the invention, and portions of the improvements may be used without others.

20 Having thus described my invention, I claim:

1. A sound-subduing casing for a type-writing machine, including a body-portion having an opening at the front for the typewriter-keyboard to project forwardly therethrough, said casing also including a carriage-chamber which overhangs the body of the casing, said body-portion including an open front plate, and also including side 25 walls and a rear wall, said side walls diverging from their bottoms to form overhangs, the upper end of each side wall forming a lower part of said carriage-chamber, means for attaching said side walls to said rear 30 wall, panels being spaced from said side walls and coextensive therewith to form air-pockets, means attaching said panels to said side walls, a panel spaced from the rear wall and coextensive therewith to form an air-pocket, means for attaching said rear 35 wall panel, and means attaching said front and rear walls to the front and rear edges of said side walls.

2. A sound-subduing casing for a type-writing machine, including a body-portion having an opening at the front for the typewriter-keyboard to project forwardly therethrough, said body-portion including an open front plate, and also including side 40 walls and a rear wall, means for attaching said side walls to said rear wall, panels being spaced from said side walls and coextensive therewith to form air-pockets, means for attaching said panels to said side walls, a 45 panel spaced from the rear wall and coextensive therewith to form an air-pocket, means for attaching said rear wall panel, means attaching said front and rear walls to the front and rear edges of said side 50 walls, and strips of sound-absorbing packing bordering the edges of all of said panels, for dampening the vibrations of the walls and panels, and preventing escape of sound vibrations from said air-pockets.

3. A sound-subduing casing for a type-

writing machine, including a body-portion having an opening at the front for the typewriter-keyboard to project forwardly therethrough, said casing also including a carriage-chamber which overhangs the body of the casing, said body-portion including an open front plate, and also including side walls and a rear wall, said side walls diverging from their bottoms to form overhangs, the upper end of each side wall forming a lower part of said carriage-chamber, means for attaching said side walls to said rear wall, panels being spaced from said side walls and coextensive therewith to form air-pockets, means attaching said panels to said side walls, a panel spaced from the rear wall and coextensive therewith to form an air-pocket, means for attaching said rear wall panel, means attaching said front and rear walls to the front and rear edges of said side walls, and strips of sound-absorbing packing bordering the edges of all of said panels, for dampening the vibrations of the walls and panels, and preventing escape of sound vibrations from said air-pockets.

4. A sound-subduing casing for a type-writing machine, including a body-portion having an opening at the front for the typewriter-keyboard to project forwardly therethrough, said casing also including a carriage-chamber which overhangs the body of the casing, said body-portion including an open front plate, and also including side walls and a rear wall, said side walls diverging from their bottoms to form overhangs, the upper end of each side wall forming a lower part of said carriage-chamber, means for attaching said side walls to said rear wall, panels being spaced from said side walls and coextensive therewith to form air-pockets, means attaching said panels to said side walls, and means attaching said front and rear walls to the front and rear edges of said side walls.

5. In a casing for a typewriting machine including a frame and a keyboard, the combination of a sectional body-part and a cover therefor, a felt lining fast to the side of the front wall of said body-part, an opening through both the front wall and the felt lining through which the keyboard protrudes, and means for forcing the machine against the lining of the front wall for effectively enclosing the noise in said casing, said means including a rock-shaft at the rear of the machine having mounted thereon at one end a shoe bearing on the frame of the machine and having at the other end a resilient arm and means for locking said arm in its effective position.

6. A sound-subduing casing for a type-writing machine, including a body-portion having an opening at the front for the typewriter-keyboard to project forwardly there-

- through, said body-portion including an therefor, a spring operatively connected for effectively raising said cover when the lock is released, and means within the lock for adjusting the opening formed between the body-part and the cover, said means comprising an adjustable plate co-operating with said lock for effectively controlling the width of said opening. 70
- 10 7. The combination with a typewriting machine comprising a carriage and a finger-piece on said carriage, of a sound-deadening casing for said machine, a cover, an opening in the front of the casing formed by the cover being left partly open, through which the finger-piece extends, upper and lower co-operating cushions extending along said opening for effectively sealing said opening against the emission of sound, said cushions comprising resilient felt wads in the form of strips abutting against each other, and means for removably supporting said felt strips, including metal strips fast one to the cover and the other to the casing, each metal strip extending the full length of said opening, each of said metal strips forming a channel in which the felt strip may be inserted, said channels opposed to each other. 85
- 20 8. The combination with a typewriting machine comprising a carriage and a finger-piece on said carriage, of a sound-deadening casing for said machine, a cover and a lock therefor, an opening in the front of the casing formed by the cover being left partly open, through which the finger-piece extends, a cushion extending along both sides of said opening for effectively sealing said opening against the emission of sound, said cushions comprising resilient felt wads in the form of strips abutting against each other, means for supporting said felt strips, and means for effecting relative adjustment of the felt strips. 90
- 30 9. The combination with a typewriting machine comprising a carriage and a finger-piece on said carriage, of a sound-deadening casing for said machine, a cover and a lock therefor, an opening in the front of the casing formed by the cover being left partly open, through which the finger-piece extends, a cushion extending along both sides of said opening for effectively sealing said opening against the emission of sound, said cushions comprising resilient felt wads in the form of strips abutting against each other and yielding locally to the finger-piece, means for supporting said felt strips and means for effectively adjusting the pressure of the felt strips one against the other, the latter means including an adjustable member co-operating with said lock for controlling the width of the opening between the casing and the cover therefor. 105
- 40 10. In a casing for a typewriting machine, including a body-part, a cover and a lock
- 115 11. A sound-subduing casing for a type-writing machine including a body-portion having an opening at the front for a type-writer-keyboard to project forwardly there-through, said body-portion including an open front plate and also including side walls diverging from bottom to top and a rear wall, said side walls each cast in one piece with a bottom flange, means for attaching said side walls to said rear wall and said front wall, panels spaced from said side walls and coextensive therewith and secured against said flanges at their lower ends and having securing means at their upper ends, said panels being spaced from said side walls to form air-pockets, and means for attaching said front and rear walls to the front and rear edges of said side walls. 120
12. A sound-subduing casing for a type-writing machine including a body-portion having an opening at the front for a type-writer-keyboard to project forwardly there-through, said body-portion including an open front plate and also including side walls diverging from bottom to top and a rear wall, said side walls each cast in one piece with a bottom flange, means for attaching said side walls to said rear wall and said front wall, panels spaced from said side walls and coextensive therewith and secured against said flanges at their lower ends and having securing means at their upper ends, said panels being spaced from said side walls to form air-pockets, means for attaching said front and rear walls to the front and rear edges of said side walls, and felt strips extending along the edges of said pockets to seal the same. 125
13. A sound-subduing casing for a type-writing machine including a body-portion having an opening at the front for a type-writer-keyboard to project forwardly there-through, said body-portion including an open front plate and also including side walls diverging from bottom to top and a rear wall, said side walls each cast in one piece with a bottom flange, means for attaching said side walls to said rear wall and said front wall, panels spaced from said side walls and coextensive therewith and secured against said flanges at their lower ends and having securing means at their upper ends, said panels being spaced from said side walls to form air-pockets, means for attaching said front and rear walls to the front and rear edges of said side walls, felt strips extending along the edges of said pockets to 130

seal the same, and a panel spaced from said rear wall and co-operating therewith to form an air-pocket, means attaching said rear panel to said rear plate and said side walls, 5 and felt strips sealing the edges of said rear pocket.

14. In a casing for a typewriting machine including a frame and a keyboard therefor, the combination of a built-up body-portion 10 including a front section and a rear section fastened to end frames and mounted on a

base-plate, an opening in the front section through which the keyboard protrudes, a front closure under said keyboard including an upwardly-extending portion which forms 15 an integral part of said base-plate, a felt lining on the inner side of said closure, and means for holding said lining on said closure, the latter means comprising a resilient strip supported at the ends and bearing on the 20 lower edge of said felt lining.

WILLIAM A. DOBSON.
